UNITED STATES PATENT OFFICE

WILLIAM A. DOBSON, OF BRIDGEPORT, CONNECTICUT, ASSIGNOR TO UNDERWOOD
ELLIOTT FISHER COMPANY, OF NEW YORK, N. Y., A CORPORATION OF DELAWARE

TYPEWRITING MACHINE

Application filed January 16, 1928. Serial No. 247,018.

This invention relates to machines for typing words together with numerals and fractions, and one of the objects of the invention is to simplify a machine in which it is desired to use an excessive number of fractions and special characters, that is, more than can be accommodated in an ordinary four-bank typewriter having a single case-shaft.

According to the present invention, there is used only a single shift and the keyboard has a system of alphabet-keys all connected to print capital letters, and it also has on the same keys a system of numerals and a system of fraction-characters, and punctuation and other marks, giving a great range or flexibility in typing numbers and fractions, especially for monetary and other purposes.

One of the features of the invention is in the nature of means for avoiding the taxing of the mind of the operator in remembering to shift the platen up and down for letters or figures as the case may be, said shifting being necessarily frequent where every typed word is followed by a typed number, that is, where words and numbers alternate across the page in the line of writing, which is a use for which this machine is especially suitable. It will be understood that, if an attempt should be made to effect such a result with an ordinary four-row typewriter, even though it printed no lower-case letters, there would need to be much shifting done and much study of the keyboard in connection with the shifting owing to the fact that a single set of keys comprising four rows would be insufficient to carry a complete alphabet and a complete set of numerals, fractions and punctuations on the same shift, and the use of the shift-key on such a machine would necessarily be difficult and tiresome, and liability of errors would be great where it was desired to write words and numbers alternately along the line of writing across the page.

According to the present invention, a single-shift machine is employed, and twenty-six keys are devoted to capitals on one shift and the same keys are devoted to numerals, fractions and punctuation marks on the other shift. There may be also three other keys, each having two appropriate types.

In using this machine, the keys are operated first to type a word and then the operator depresses a space-bar to secure a space after the word on the work-sheet, and, in so doing, he automatically shifts the machine so that numerals, fractions and punctuation marks will be typed at the next operations of the type-keys. The machine is now used for typing the numbers. Having completed the numbers the operator again uses a space-bar to space the numbers from the succeeding word on the work-sheet, and, in so doing, he automatically resets the machine for writing letters. So the work proceeds, words alternating with numbers, using the different shift-positions of the typewriter alternately and automatically without any special attention on the part of the operator, thus avoiding errors and greatly expediting the work.

For the purpose of the invention, the word-spacing of the machine is effected by means of either one of two space-bars, one of which is operated after typing a word, and the other of which is operated after typing a number. One of these space-bars is operatively connected to appropriate case-shifting mechanism, which co-operates with a releasable latch for automatically latching the case-shifting mechanism in upper-case position. The other space-bar releases the latch.

The machine is also capable of writing a succession of words to form a line, the same as in a usual typewriter, and in this case the operator uses that one of the two space-bars which has been arranged for use after writing figures. That is, he uses the type-keys to write the word, and then uses one space-bar if he expects to write another word immediately, or the other space-bar if he expects to write a number immediately. Each of the space-bars will affect the letter-space mechanism, but where an operator desires to write a succession of words he uses the space-bar which does not affect the shift-mechanism.

Other features and advantages will hereinafter appear.

In the accompanying drawings,

Figure 1 is a fragmentary cross-sectional

view, front to rear, through a typewriting machine having my invention applied thereto.

Figure 2 is a detailed view illustrating 5 means of adjusting the locking pin for the platen-shifting mechanism.

Figure 3 is a plan view of a keyboard suitable for use in typing telegrams and other communications relating to monetary transactions. 10

Figure 4 is a fragmentary cross-sectional view, front to rear, of the structure shown in Figure 1, the platen-shifting space-bar being illustrated in operated position and the 15 shift-frame locked in upper-shift position.

Figure 5 is a view similar to Figure 4, the shift-frame-releasing space-bar being shown in operated position and the platen-shift-frame shown at the moment of beginning its 20 descent to normal position.

Figure 6 is a fragmentary top view of mechanism operatively connecting the space-bars with the escapement-mechanism.

Figure 7 is a fragmentary perspective view 25 of the space-bars of the invention and interponents for operatively connecting them with the escapement-mechanism and the platen-shift-frame of the typewriting machine.

The present invention may be applied to a 30 portable typewriting machine, which is in general similar to that disclosed in a patent granted to me, No. 1,335,956, dated April 6, 1920. Each of a plurality of type-bars 10 may have a numeral type 11 and a capital 35 letter type 12, and may be swung against a platen 13 by depression of a key 14 operatively connected with a type-bar by usual instrumentalities not shown. The platen is mounted on a platen-shaft 15 journaled in 40 end plates 16 of a sheet-metal carriage 17, which may be pulled to the left by a usual spring, not shown, under control of escapement-mechanism generally designated as 18.

The carriage travels on rollers 20 and ball-bearings 21 which run on tracks 22 and 23 respectively, the tracks being fastened rigidly between side plates 24 of a shift-frame generally designated as 25. For guiding the shift-frame, each of the side plates is pivotally fastened adjacent its forward side to the forward end of a long rearwardly-extending arm 26, whose rear end is pivoted on a stud 27 in the main frame 28. Also each side plate 24 is pivotally connected adjacent its lower 55 edge and in the rear of the forward end of the arm 26 to a stud 29 in the forward end of a rocking arm 30, which is securely fastened on a lateral rock-shaft 31 journaled in the main frame 28. The escapement-mechanism 18 includes a rack 32 fastened on the carriage 17 and meshing with a pinion 33, which is fastened to an escapement-wheel 34. A dog-rocker 35 carries a loose dog 36 and a fixed dog 37, both of which are mounted for 60 operatively engaging the escapement-wheel 65

34, so as to permit it to rotate a step at a time. The construction and operation of the escapement-mechanism 18 may be the same as that disclosed in Patent No. 1,332,972, granted to George W. Campbell March 9, 1920. 70

For bringing the platen 13 to position for engagement with a numeral type 11, which is indicated by a dot-and-dash position in Figure 4, the shift-frame 25 is swung upwardly on the arms 26 and 30 by rocking the shaft 31 clockwise. A forwardly-extending operating arm 38 is fastened rigidly on the shaft 31 adjacent the left end thereof, and has a laterally-bent tab 39 at its forward end. 75

In typing certain data relating to monetary 80 transactions, it is common in some offices to alternately type a group of letters and a group of figures with the usual spacing between the groups. To reduce the number of platen-shifting operations required in typing 85 such data, there is provided in the machine embodying the present invention a left-hand and a right-hand space-bar 40 and 41, respectively, which are positioned in lateral alignment with each other at the front of the usual 90 keyboard, each of which operates the escapement-mechanism 18 and has an operative connection with the platen-shift mechanism of the machine. The space-bar 41 is carried by a right-hand and a left-hand space-bar-lever 42, 43, the rear end of each lever being fastened rigidly to a rock-shaft 44, whose right end is journaled in a depending ear 45 on a right-hand side plate 46 of the main frame 28. The left end of the shaft 44 is journaled in a right-hand ear 47 of a bracket-plate 48, which may be fastened by screws 49 to a usual key-lever guide-comb 50, which is positioned between the right-hand side plate 46 and a left-hand side plate 51 of the main 95 frame. 100

It is found desirable to shift the platen 13 upon depression of the space-bar 40, and, to that end, interponents between the latter and the arm 38 are provided, as follows: two space-bar-levers 52 carry the space-bar 40 on their forward ends, and have their rear ends fastened to a rock-shaft 53, whose right end is journaled in an ear 54 of the bracket 48 and whose end is journaled in a depending flange 55 on the side plate 51. An upwardly-extending rock-arm 56, fastened rigidly on the shaft 53, carries an inreaching lateral pin 57 on which is loosely mounted a roller 58, which arrangement swings the roller counter-clockwise upon depression of the space-bar 40. A lever 59 extending from an engagement with the roller 58 to the tab 39 is pivoted therebetween on a stud 60 in an integral standard 61 on a cross-bar 62, which is fastened between the side plates 46 and 51. The upper edge of a forward portion 63 of the lever 59 is disposed against the lower side of the roller 58 and curves upwardly and forwardly in front of the same with a radius 105 110 115 120 125 130 135 140 145 150 155 160 165 170 175 180 185 190 195 200

greater than the radius of the roller, whereby it may have a cam-like engagement with the roller. The rear end of the lever 59 engages under the laterally-extending tab 39, and, when the space-bar 40 is depressed, the roller 58 is swung forward and cams the forward end of the lever 59 down, and swings the tab 39 up, thus rocking the shaft 31 and raising the platen to upper-shift position, which is determined by an inturned flange 64 on each side plate 24 striking against a screw 65 held in an upwardly-extending bracket 66 of a mounting plate 67, which may be riveted to a rear cross-bar 15 68 fastened between the side plates 46 and 51 of the main frame 28. A screw 69 through the forward end of each mounting plate 67 engages the adjacent flange 64 and determines the lower-case or normal position of 20 the platen. The stop-screws 65 and 69 are each provided with a lock-nut 70.

The upwardly-curved forward portion 63 of the lever 59 also serves as a stop to arrest the forward movement of the roller, and the 25 downward movement of the space-bar 40, as can be readily seen from inspection of the relative positions of the roller 58, the lever 59 and the arm 56, as shown in Figure 4.

To lock the platen in upper-case position, a laterally-extending pin 71 is fastened in the rock-arm 38 a short distance to the rear of the rear end of the lever 59. A locking trigger or prop, generally designated as 72, is pivotally mounted on a stud 73 screwed 35 into an upturned flange 74 of a mounting plate 75 fastened by rivets 76 to the bottom side of the cross-bar 62. The trigger 72 has an upright body 77 and an integral rearwardly-extending elbowed arm 78 at the upper end of the body 77. A concave locking notch 80 is cut out of the trigger at the intersection of the upper edge of the arm 78 and the forward edge of the upright body-member 77. A tensile spring 81, which has its rear end fastened to a tongue 82 on the body 77, and its forward end fastened to a pin 83 in the flange 74, tends to swing the trigger 72 forwardly. In Figure 1 is shown the normal or ineffective position of the trigger, whose forward edge is urged against the pin 71 in the rock-arm 38. It will be readily seen from an inspection of Figures 1, 4 and 5 that, upon depressing the space-bar 40 and concomitantly raising the arm 38, the pin 71 will ride up along the forward edge of the upright trigger-body 77 until it reaches the notch 80, when the trigger-body will be snapped forwardly by the spring 81 and the notch seated against the pin, as shown in 50 Figure 4, which engagement operates as a prop to support the weight of the platen and shift-frame and prevents the return to normal of the shift-frame operating arm 38 upon release of the space-bar 40.

65 For operating the escapement-mechanism

18 by the space-bar 40 an operative connection is provided between the two elements including an upwardly-extending inverted L-shaped actuator-member 84 fastened on the shaft 53 a short distance to the right from the arm 56. A rearwardly-extending arm-portion 85 of the actuator is provided with a lengthwise slot 86. The actuator is urged toward the rear by a spring 87, which has one end fastened to a depending ear 88 of the arm 85, and the other end to a rearwardly-extending flange 89 integral with the comb 50, at the bottom edge thereof. The rear-most position of the actuator is determined by the engagement against the comb 50 of a rearwardly-extending tooth 90 on a stop-arm 91, the latter being fastened rigidly on the shaft 53 on which the actuator is mounted. A rearwardly-extending connecting rod 92 is fastened to the actuator 84 by a clevis-like member 93, having a forwardly-extending arm 94 disposed closely against each side of the actuator, and a pin 95 fastened in the ends of the arms 94 and extending through the slot 86. To the rear end of the rod 92 is fastened a link-member 96, which has a rearwardly-extending upwardly-curved arm 97.

To operatively connect the link-member 96 with the dog-rocker 35, Figure 6, provision is made of a swinging member 100 herein-after called a dog-rocker operator which has a body 101 extending rightwardly to a point adjacent the usual left end of the dog-rocker. At the right end of the body an integral flange 102 is bent rearwardly a short distance, and carries an integral finger 103, which bends to the right behind the left end of the dog-rocker. At the left end of the body 101 an integral wrist-member 104 bends forward and is fastened to the link 96 by a shoulder-screw 105, which passes loosely through a hole in the link-member, and is threaded into the wrist 104 as a crank-pin. To permit the operator 100 to swing forwardly and backwardly, it is mounted on the upper ends of two arms 106 of a U-shaped rocker 107, which is fastened on an axle-pin 108 journaled in two bearing-plates 109 which are mounted on the cross-bar 68.

In the normal position of the space-bar 40 and escapement-mechanism 18, as shown in Figures 1 and 7, the pin 95 is disposed against the rear end of the slot 86. It will be seen that a slight initial downward movement of the space-bar 40 will move the escapement-mechanism, and thereafter the platen is shifted and locked in upper-case position, but the escapement-mechanism will not letter-space the carriage until the space-bar is released.

Thus it will be seen that the operation of the space-bar 40, after writing a group of capital letters, is effective to letter-space the platen, shift it to upper-shift position, and

lock it therein preparatory to typing a group of numerals. After writing a group of numerals, it is desirable, according to one use of the invention, to write a group of capital letters with the usual letter-space between the groups. To position the platen with a minimum of operations for typing the last-mentioned group, means, to be presently described, are provided for making the space-bar 40 effective for releasing the locking trigger 72, while concomitantly operating the escapement-mechanism. The space-bar-lever 43 has a depending ear 110, with a collar 112 fixed thereto, through which passes a laterally-disposed shaft 111 pinned to the collar. The shaft 111 extends leftwardly to the side plate 51 and is journaled therein, a collar 113 on the shaft holding it against leftward displacement. An inverted L-shaped rocking arm 114 is fastened on the shaft 111 a short distance to the left of the plane of the actuator 84. A spring 115, which has one end fastened to a pin 116 in a rearwardly-extending portion 117 of the rocking arm 114, and the other end to the flange 89, normally urges the rocking arm rearwardly, the rearmost position of the latter may be determined by the bottoming of the portion 117 in a slot in the comb 50. To make the depression of the space-bar 41 more effective for turning the shaft 111 and rocking the arm 114, the shaft may be formed with two right-angle bends, so as to provide a crank-like element 118 in the shaft between the ear 110 and the arm 114 (Figure 7).

An operative connection between the arm 114 and the locking trigger 72 includes a rearwardly-extending connecting rod 120, whose forward end is loosely fastened to the rear end of the arm-portion 117 by a clevis 121, which has an arm 122 engaging against each side of the arm-portion 117 and a pin 123 fastened in the ends of the arms 122 and extending loosely through a hole in the arm-portion 117. A cam-acting plate 125 is fastened on the rear end of the rod 120, and extends rearwardly therefrom adjacent the wrist 104. The plate 125 has an enlarged rear end portion 126 provided with a downwardly and forwardly curved cam-slot 127, which is arranged to ride upon the shoulder-screw 105.

In the normal position of the machine (Figures 1 and 7), the screw 105 is disposed at the rear end of the slot 127. This position of the screw in the slot permits a slight initial depression of the space-bar 41 to swing the dog-rocker operator 100 forward. It also permits a depression of the space-bar 40 to swing the dog-rocker operator forward without affecting the space-bar 41, since, in the latter case, the screw 105 will ride idly in the slot 127. When the space-bar 41 is depressed, and the operator 100 is swung forward, the connection-rod 92 and clevis 93 are moved

forward, but the actuator 84 and space-bar 40 are not affected since the pin 95 in the clevis 93 will slide idly forward in the slot 86.

The lower edge of the plate 125 adjacent its forward end is arranged with a downwardly and rearwardly sloping cam-edge 128 for a purpose which will presently appear. It will be noted that, in normal position, the screw 105 is disposed a short distance in front of a vertical plane through the axle-pin 108 (Figure 1), and consequently when the space-bar 41 is depressed the screw will be swung downward as well as forward, and the cam-edge 128 is thereby caused to move down as well as forward. When the platen-shifting space-bar 40 is operated, the locking trigger 72, in a way described above, is swung forward, and a pin 129 in the rear end of the trigger-arm 78 is swung up against the cam-edge 128 of the plate 125, and remains in this position while a group of upper-shift characters or numerals are typed. The subsequent depression of the space-bar 41 causes the forward and downward movement of the cam-edge 128 to press the pin 129 down and swing the trigger 72 clockwise until the locking notch 80 is disengaged from the pin 71, which permits the latter and the rocking arm 38 to be restored by the weight of the carriage to normal lower-shift position. Upon release of the space-bar 41, the spring 115 is effective to return the cam-plate 125 rearwardly to normal position, and a usual spring 130 returns the dog-rocker 35 to normal, permitting the escapement-mechanism to letter-space the platen one step, the escapement-mechanism 18 is operated, and the machine is in condition to have ordinary lower-shift typing performed.

It will be noted that the advantageous arrangement of the space-bars 40 and 41 in alignment with each other at the front of the machine, to form substantially a single space-bar divided in two sections, permits the operator, at all times, to conveniently depress the space-bar 40 with the left hand and the space-bar 41 with the right hand. It had been found that operation of the space-bar 40 by the left hand before a group of figures, and operation of the space-bar 41 by the right hand before a group of capitals are done almost unconsciously after a short time, which makes for speed and accuracy.

In Figure 2 is illustrated an advantageous adjusting means to permit a pin 131, carried by the platen-shift-operating roll 58, to be adjusted with respect to the trigger 72, whereby the platen-shift-frame may be accurately locked in its upper-case position, as determined by the flange 64 and the screw 65. An adjusting plate or strip 132 is pivoted against the inner face of the arm 38 on screw 133 threaded in the arm. The pin 131 is fixed rigidly in the plate 132. An integral transversely-extending lip 134 is arranged at the

forward end of the plate 132 to extend over the upper side of the arm 38, and is provided with a tapped hole through which is threaded an adjusting screw 135, which bears

5 against the upper side of the arm 38. A slot 136 is arranged in the plate 132 between screw 133 and the lip 134, and is curved about the axis of the screw 133 as a center. A screw 137 passes through the slot 136, and is threaded into the arm 38 and extends therethrough to receive a lock-nut 138.

Variations may be resorted to within the scope of the invention, and portions of the improvements may be used without others.

10 15 Having thus described my invention, I claim:

1. In a single-shift typewriting machine arranged for typing letters in lower-shift position and for typing numerals in upper-

20 shift position, the combination with a platen, an escapement-mechanism, and a platen-shifting mechanism including a rock-arm with stops to limit the shift of the frame, of a space-bar for operating said escapement-

25 mechanism, an operative connection between said space-bar and said rock-arm effective for lifting said platen to upper-shift position upon operating said space-bar for word-spacing a group of letters typed in lower-

30 shift position from an immediately following group of figures to be typed in upper-shift position, a releasable prop under the rock-arm for automatically propping said arm against a stop-position and supporting said platen in upper-shift position, a second space-bar for operating said escapement-

35 mechanism, and an operative connection between said second space-bar and said prop for withdrawing said prop from under said

40 rock-arm to restore the frame to normal low position upon depression of said second space-bar and word-space said group of figures from an immediately following group of letters.

45 2. In a typewriting machine of the class described, in combination, a platen-shift mechanism including an operating rock-arm and a locking pin supported by said arm, mechanism including a space-bar having

50 connections effective for rockably lifting said arm to raise the platen of said machine, a pivoted locking device on the frame of the machine effective for engaging under said pin after the lifting of the platen, a second

55 space-bar aligned with the first-named space-bar, letter-spacing escapement-mechanism, and a train of mechanism operatively connecting said last-named space-bar and said escapement-mechanism, including a cam-link effective for camming said locking device to

60 ineffective position to release the locked-up platen upon operation of said last-named space-bar.

65 3. The structure described in claim 2, characterized by a construction of said connecting

mechanism effective for releasing the carriage-holding escapement-mechanism to letter-space the platen after said locking device is released.

4. In a typewriting machine of the class described, the combination with a platen-

shift mechanism, of a space-bar at the front of the machine, and interponents between said space-bar and said mechanism for operating the latter upon depression of said

space-bar for letter-spacing the platen, said interponents including a lever extending from an operative connection with said shift-

ing mechanism toward the front of the ma-

chine, said lever being pivoted intermediate its ends, a cam-roller engaging the forward end of said lever, and means for moving said roller downwardly against the forward end of said lever upon depression of said space-

bar, the forward end of said lever being

45 curved upwardly to serve as a stop for said roller and also as a cam to permit said roller to swing said lever about its pivot.

5. In a typewriting machine of the class described, the combination with a platen-

shift frame and a rock-arm effective for rais-

ing said shift-frame to upper-case position, of a lever having one end operatively engag-

ing said rock-arm and the other end arranged

55 with a cam-element, a roller engaging said

cam-element, a space-bar, and interponents

between said space-bar and said roller ar-

ranged for operatively engaging the latter

against said cam-element to move said lever

about its pivot for swinging said rock-arm

and raising said platen.

6. In a typewriting machine of the class described, the combination with a platen-

shift frame and a rock-arm effective for swing-

105 ing said shift-frame to its upper-case position, of a forwardly-extending lever hav-

ing its rear end operatively engaging said

rock-arm and its front end curved upwardly,

a roller disposed against the upper curved

side of said lever, a rock-arm on which said

roller is mounted, a lateral shaft below said

roller on which said arm is mounted, a space-

bar, and levers fast on said shaft supporting

110 said space-bar on their forward ends, where-

by the depression of said space-bar is effec-

tive to swing said roller forwardly and cam

the curved end of said lever down, the pos-

115 titioning of said shaft, said rock-arm and

curved lever-end being effective to limit the

forward movement of said roller.

7. The structure described in claim 6, char-

acterized by means normally urging said roll-

er rearwardly, including a stop-member on

120 said shaft arranged for engaging against a

fixed element of said machine to limit the

rearward movement of said roller.

8. In a typewriting machine having a

platen-shift frame, the combination with a

forwardly-extending rock-arm for raising

125 said shift-frame to its upper-case position,

130 and a connecting mechanism operatively

of means for releasably locking said arm in its uppermost operated position, including a laterally-extending pin carried by the forward portion of said arm, a locking trigger pivoted below said pin and having an upwardly-extending body and a rearwardly-extending elbow-member, a spring for urging said trigger forwardly, said trigger-body being positioned whereby its forward edge is normally pressed against the back side of said pin, an upwardly and rearwardly sloping locking notch at the junction of said trigger-body in said elbow-member arranged for receiving said pin when the latter is swung upwardly past the front edge of said body, a laterally-extending pin fast to the rear portion of said elbow-member, a space-bar, and instrumentalities operatively connected with said space-bar and arranged for pressing downwardly on said last-named pin and swinging said notch out of locking engagement with said last-named pin on depression of said space-bar.

9. The structure described in claim 8, characterized by an escapement-mechanism, and a forwardly-movable connection between the space-bar and said escapement-mechanism, including a cam, said cam being effective to press downwardly on the pin in the elbow-member.

10. In a typewriting machine having a platen-shift frame, the combination with a forwardly-extending rock-arm for raising said shift-frame to its upper-shift position, of means for releasably locking said arm in its upper-shifted position, including a lateral pin carried by the forward portion of said rock-arm, a locking trigger pivoted below said pin and having an upright body and a rearward elbow-member, a spring for urging said trigger against said pin, a locking notch in said trigger-member arranged for receiving said pin, a lateral pin fast to said elbow-member, a space-bar, a case-shifted escapement-mechanism, a forwardly-movable connection between the space-bar and escapement-mechanism including a cam effective to depress the pin on the elbow-member and withdraw the trigger from under a raised rock-arm pin, and a pivoted dog-rocker operator mounted on the frame and connected to the space-bar-moving connection to vibrate the dog-rocker at either case-shift position thereof to word-space the platen.

11. In a typewriting machine having a shift-frame, in combination, an upwardly-movable operating rock-arm for said shift-frame, a lateral pin supported by said rock-arm, a locking trigger arranged to engage under said pin when said arm is moved to its operated position, and means for adjustably positioning said pin transversely to the long axis of said arm, including a plate-member pivotally fastened on a side of said arm and having said pin fastened thereto, and devices

for adjustably securing said plate to said arm.

12. In a typewriting machine with an escapement mechanism having an escapement dog rocker, in combination, a vibrator pivotally mounted on the frame of the machine to vibrate said dog rocker, a crank-pin mounted on said vibrator, a pair of space-bars, and a train of mechanism between each space-bar and said vibrator, including a shaft for each space-bar, a crank-arm for each shaft, and a link connecting each crank-arm with the crank-pin on the vibrator, to operate the escapement rocker by either space-bar.

13. In a typewriting machine with an escapement mechanism having an escapement dog rocker, in combination, a vibrator pivotally mounted on the frame of the machine to vibrate said dog rocker, a crank-pin mounted on said vibrator, a pair of space-bars, and a train of mechanism between each space-bar and said vibrator, including a shaft for each space-bar, a crank-arm for each shaft, and a link connecting each crank-arm with the crank-pin on the vibrator, to operate the escapement rocker by either space-bar, one link having a pin-and-slot connection with one crank-arm, and the other link having a slot connection with said crank-pin, whereby either space-bar is operable to vibrate the escapement rocker by a forward pull on its link without movement to the other space-bar.
